T. J. FEELY.
DRAFT APPLIANCE FOR STOVEPIPES.
FILED Nov. 23, 1920.

FIG. 1.

INVENTOR
Thomas J. Feely.
BY *John Stevens*.

ATTORNEY.

UNITED STATES PATENT OFFICE.

THOMAS J. FEELY, OF DULUTH, MINNESOTA, ASSIGNOR OF ONE-HALF TO MARK ELLIOTT, OF VIRGINIA, MINNESOTA.

DRAFT APPLIANCE FOR STOVEPIPES.

Application filed November 23, 1920. Serial No. 425,943.

To all whom it may concern:

Be it known that I, THOMAS J. FEELY, a citizen of the United States, residing at Duluth, in the county of St. Louis and State of Minnesota, have invented certain new and useful Improvements in Draft Appliances for Stovepipes, of which the following is a specification, reference being had therein to the accompanying drawing.

This invention relates to draft appliances for stoves and other forms of heaters, and has for its object to provide an apparatus of this kind to be inserted within the smoke pipe of a stove or furnace and capable of producing different draft conditions.

Another object of the invention is to provide a device of this kind which may be inserted either in a straight pipe or in a pipe having an angle therein.

A further object is to provide a device which may be easily inserted within a pipe and held securely therein, but which may be easily and readily removed.

Other objects and advantages of the peculiar construction will appear in the further description thereof.

Referring now to the drawing accompanying this application and forming a part thereof, in which like reference characters indicate like parts:

Figure 1 is a transverse section through the pipe showing the mounting of the damper;

Figure 2 is a longitudinal section through a portion of the stove pipe at the discharge end of the partition member, showing a possible arrangement of the damper;

Figure 3 is a perspective view showing a stove pipe angle in section, with the present invention applied thereto; and

Figure 4 is a broken side elevation of the partition member removed and extended for use in a straight stove pipe.

The present invention comprises a partition member consisting of two sections 1 and 2, which are hinged together at their ends, as at 3. The sides of the members 1 and 2 are turned laterally in the form of flanges 4, and these flanges have pivotally secured thereto adjustable supporting bows, each consisting of two arcuate members 5 and 6. Each of the members 6 are provided with a slot 7 therein adjacent their free ends, while the members 5 are provided with bolts 8 which extend through the slots 7 and are

equipped with the nuts 9. By this arrangement it will be noted that the device may be applied to slightly varying sizes of pipes, and, when installed within a pipe, the partition portion lies spaced from the inner wall of the pipe and transverse the same for Stovepipes, of which the following is a specification, reference being had therein to the accompanying drawing.

This invention relates to draft appliances for stoves and other forms of heaters, and has for its object to provide an apparatus of this kind to be inserted within the smoke pipe of a stove or furnace and capable of producing different draft conditions.

Another object of the invention is to provide a device of this kind which may be inserted either in a straight pipe or in a pipe having an angle therein.

A further object is to provide a device which may be easily inserted within a pipe and held securely therein, but which may be easily and readily removed.

Other objects and advantages of the peculiar construction will appear in the further description thereof.

Referring now to the drawing accompanying this application and forming a part thereof, in which like reference characters indicate like parts:

Figure 1 is a transverse section through the pipe showing the mounting of the damper;

Figure 2 is a longitudinal section through a portion of the stove pipe at the discharge end of the partition member, showing a possible arrangement of the damper;

Figure 3 is a perspective view showing a stove pipe angle in section, with the present invention applied thereto; and

Figure 4 is a broken side elevation of the partition member removed and extended for use in a straight stove pipe.

ately shaped cut-away portion formed therein, as at 20, so that, when the segment 12 is disposed transverse the pipe and the segment 11 at an angle of approximately 5 45 degrees downwardly, the smoke and gases rising in the larger passage of the pipe will be forced by the segment 11 through the cut-away portion 20, and the segment 12 will aid in directing the unburned gases back to the 10 fire; through the smaller division of the flue.

As is obvious a great many different combinations of draft conditions may be produced by the regulation of the segments 11 and 12 in accordance with the different 15 conditions of combustion within the stove or furnace.

It is evident from the foregoing that I have devised a draft appliance which may be made to effectively return a portion of 20 the unburned gases to the fire for consumption which otherwise would escape with the smoke to the air.

Having thus described my invention, what I claim and desire to secure by Letters Patent, is

1. The combination with a stove pipe, of a removable longitudinally disposed division wall having an opening adjacent the upper end thereof, adjustable means attached to

the division wall for holding same in position within the pipe, and a double adjustable damper within the pipe adjacent the upper end of the division wall whereby to deflect gases passing through the pipe at the end of the wall and cause a portion of 30 same to return within the pipe. 35

2. An attachment for stove pipes including a partition member consisting of a plurality of plates hinged together at their adjacent ends for movement to lie either in a common plane or in planes at an angle to each other, adjustable supporting members carried by the plates, said plates and supporting members being adapted for engagement within a smoke pipe to effect a division 40 of the latter into two passages by the partition member, with the supporting members engaging the smoke pipe wall, and damper members adapted to be mounted in a smoke pipe for independent operation to close the 45 separate passages formed by the partition member. 50

In testimony whereof I hereunto affix my signature in the presence of two witnesses.

THOMAS J. FEELY.
